Specification for Design.

Patented Oct. 8, 1912.

Application filed August 23, 1911. Serial No. 645,659. Term of patent 7 years.

To all whom it may concern:

Be it known that I, LINDSLEY SCHEPMOES, a citizen of the United States, residing at Hasbrouck Heights, county of Bergen, and State of New Jersey, have invented a new, original, and ornamental Design for a Lamp-Fixture, of which the following is a specification.

The nature of my design is fully illustrated in the accompanying drawing, to which reference is made, and in which the figure illustrates a front elevation of the design.

My design comprises a pendant 1 having a curved continuous periphery in cross section and flaring in opposite directions from its

intermediate portion to its extremities, together with arms 2 symmetrically disposed around the pendant intermediate its ends and extending outwardly from the pendant in curved portions substantially conforming to the flared portion of the pendant adjacent thereto, having the contour and relative proportion of parts shown.

I claim:

The ornamental design for a lamp fixture as shown and described.

LINDSLEY SCHEPMOES.
